UNITED STATES PATENT OFFICE.

HENRY W. KIRCHNER, OF ST. LOUIS, MISSOURI, ASSIGNOR TO RIVER AND RAIL TRANSPORTATION COMPANY, OF ST. LOUIS, MISSOURI, A CORPORATION OF OKLAHOMA.

INTERCHANGEABLE-UNIT CAR.

1,360,412.

Specification of Letters Patent. Patented Nov. 30, 1920.

Application filed March 22, 1917. Serial No. 156,581.

To all whom it may concern:

Be it known that I, HENRY W. KIRCHNER, a citizen of the United States, residing at the city of St. Louis, State of Missouri, have 5 invented a certain new and useful Improvement in Interchangeable-Unit Cars, of which the following is a full, clear, and exact description, such as will enable others skilled in the art to which it appertains to make and 10 use the same, reference being had to the accompanying drawings, forming part of this specification.

This invention relates to railway cars, and 15 specifically to certain improvements in cars of the type known as interchangeable unit cars which are characterized by the employment of a special underframe construction arranged for the reception of specially 20 formed containers or units in which the cargo is carried. It is the intention that the units or containers so employed be individually movable and interchangeable on the underframe and among different similar cars.

25 The present application is directed to a special form of car construction whose particular object is to facilitate the handling of the units or containers by making special provision for the loading and unloading 30 thereof by means of trucks or transveyors.

Further objects are to provide a special 35 and improved form of container designed for this special use, and to provide also an improved form of securing or attaching means for retaining the containers upon the underframe.

Other and further objects will be obvious or pointed out hereinafter by reference to the accompanying drawings, in which—

40 Figure 1 is a partial side elevation of a car embodying my improved design;

Fig. 2 is an elevational detail with parts in section illustrating various features of the construction;

45 Fig. 3 is a similar elevational detail of a modified form;

Fig. 4 is a perspective view of my improved form of container;

Fig. 5 is a perspective detail illustrating 50 the securing means; and

Fig. 6 is a perspective showing a form of transveyor truck which may be employed in the operation of my car.

Referring to these drawings by the char-

acters of reference applied, let it be understood that the numeral 1 designates generally longitudinal members of the car underframe, which longitudinal members may be of any desired number, form and relative disposal. These longitudinal members are 60 connected by suitable transverse members in any of the conventional fashions, and the underframe construction so formed is equipped for support upon any appropriate form of railway car truck.

65 Suitably supported upon the underframe formed by the longitudinal and transverse framing members are seat members 4 directed transversely of the underframe and suitably spaced for the reception and retention 70 of the interchangeable units or containers 5.

In the form illustrated in Fig. 2, the seat members 4 are in the form of angle bars applied to the underframe members and having their upstanding flanges arranged to 75 engage the lateral portions of the lower extremities of the containers. The containers in this form are provided with depending supporting portions 6 which space the bottoms of the containers apart from the seat 80 members 4. The seat members 4 have transversely extending portions forming trackways 7 extending below the bottoms of the containers and adapted to support a truck of the proper gage to permit its being rolled 85 thereon to a position below the containers. The truck which I propose to use in this connection is of the type commonly known as a transveyor, and is characterized by the provision of an adjustable platform portion 90 upon which the load is carried, and which platform portion may be raised and lowered at will to raise or lower the load relative to the running gear. One form of this truck is illustrated in Fig. 6. To accommodate 95 the front or intermediate wheel, an additional track member 7' is disposed upon the underframe structure properly spaced relative to the track portions 7. In the employment of a car of this character, it is intended that the cargo shall be disposed in the containers 5, and the containers may be loaded on the car by placing them on trucks by which they are conveyed onto the seat portions provided on the car frame, the 100 trucks, of course, being rolled along the trackways 7 and 7' until the container is brought to the proper position over its seat,

and the truck then manipulated to lower the container until it rests upon the seat, whereupon the truck may be withdrawn from below it. When thus positioned on the seat, the container may be secured by any appropriate securing means, that illustrated comprising a combination of revoluble shafts 8 which may be operated from a suitable hand crank, which shafts carry engaging members 9 projecting outwardly therefrom and formed with portions adapted to engage suitable keepers on the containers. In the present embodiment, these keepers are formed by the provision of apertures 10 in the depending supporting portions 6 of the container, and the engaging members 9 are in the form of hooks adapted to swing into the said apertures. When so positioned, the retaining members operate to secure the containers firmly in their seats to insure their safe carriage to the point of delivery.

In Fig. 3, a modified arrangement is illustrated wherein the body of the container rests directly upon the seat member and the track numbers 7 and 7' are disposed in a lower plane. The utilization of this arrangement is effected in the manner as above described with reference to the preferred form.

By virtue of this arrangement, the handling of the containers is greatly facilitated, and the necessity for expensive special equipments such as derricks or cranes is obviated.

I am aware that the invention is susceptible of embodiment in forms differing in various particulars from those herein illustrated and described without departing from the intended scope of the appended claims.

What I claim is:

1. In a car of the class described, the combination of an underframe, cargo containers removably supported thereon, a plurality of spaced truck runways provided on said underframe and disposed below and spaced apart from the bottoms of said containers and means arranged in the spaces between the truck runways for engaging the

lower portions of the cargo containers and 50 locking them in position on the underframe.

2. In a car of the class described, the combination with an underframe, a plurality of transversely disposed truck runways arranged on said underframe, a series of 55 movable containers adapted to be positioned on parts of said runways, the bottoms of which containers are spaced apart from said runways, and means arranged between the truck runways for engaging the lower portions of said containers and locking them in position upon the runways.

3. In a car of the class described, the combination with an underframe, of a series of movable containers adapted to be interchangeably positioned upon said underframe, portions of certain of the walls of each container being extended downwardly to form supporting legs for the container, and said downwardly extending portions being provided with apertures adapted to receive holding devices.

4. In a car of the class described, the combination with an underframe, of a plurality of pairs of transversely disposed seats on 75 said underframe, which seats are adapted to receive movable containers, and truck runways on said underframe between said seats and below the bottoms of the containers positioned on said seats.

5. In a car of the class described, the combination with a supporting underframe, of pairs of seat members transversely disposed thereupon, portions of which seat members are extended inward to form track members, a third track member transversely disposed upon the underframe and arranged intermediate the tracks on the seat members, cargo containers adapted to rest on said seat members, and means arranged outside said seat members and adapted to engage the lower portions of the cargo containers for locking the same in position on said seat members.

In testimony whereof I hereunto affix my 95 signature in the presence of two witnesses, this 20th day of March, 1917.

HENRY W. KIRCHNER.
